MEANS FOR OPERATING FIRELESS LOCO-
MOTIVES

Paul Gilli, Vienna, Germany

Application December 3, 1938, Serial No. 243,726
In Germany December 3, 1937

3 Claims. (Cl. 105—37)

This invention relates to fireless locomotives. From the economic and operating point of view the utilization of fireless locomotives offers a number of substantial advantages over the use of locomotives which include a fire box, although the usefulness of fireless locomotives of known design is limited owing to the small radius of action of such vehicles.

The radius of action of fireless locomotives can however be considerably increased by using a higher accumulator pressure and it is the chief object of the present invention to provide means for operating locomotives of this kind with such higher pressure.

According to the invention a throttling member is disposed in the discharge line of a high-pressure accumulator tank or tanks which is adapted to throttle the steam to the normal working pressure of the locomotive cylinders, while a compensating or equalizing vessel is arranged between said throttling member and the cylinders. The volume of the equalizing vessel is preferably so proportioned as to correspond to the displacement of the steam cylinder and including the volume of the connecting conduits it should amount to at least double, but preferably a greater multiple of the cylinder displacement volume.

In the known types of fireless locomotives, owing to the irregular amounts of steam drawn off by the individual strokes of the piston, great pressure variations occur in the steam line between the accumulator and the cylinder. In addition to the above disadvantage there is the further drawback that the mean pressure of admission to the cylinder and thus also the efficiency of the steam engine is comparatively low. By providing a compensating vessel in accordance with the invention a practically constant pressure of admission can be obtained, said pressure being higher than in the known plants, and moreover in this manner the specific steam consumption is greatly decreased.

It is preferable to superheat the throttled steam in a manner known per se by means of heating zones, and the compensating vessel is therefore preferably arranged beyond the superheater, with respect to the direction of air flow.

It is advantageous to arrange for the auxiliary devices associated with the locomotive, such as for example vacuum brake air pump, Knorr steam pump, whistle, dynamo, train heating and the like to be supplied with steam from the compensating vessel, some or all of such devices being connected to the lowest point of said vessel

in order to avoid an accumulation of water therein. In those cases where superheated steam is undesirable or unsuitable for certain auxiliary devices, the steam for these is withdrawn from the steam line ahead of the superheater.

It is particularly advantageous to arrange the compensating vessel inside the insulation of the accumulator tank or tanks and in such cases said vessel is preferably designed to have a small diameter and correspondingly greater length. In the case of locomotives having three accumulator tanks arranged within a common insulation the compensating vessel can with advantage be located within said insulation between the two lower tanks. In certain cases the compensating vessel may be arranged in the interior of the accumulator and a very simple design for this purpose consists in making the cubic capacity of the superheater so large as to give it the effect of a compensating vessel.

It is satisfactory to draw the steam for the auxiliary devices through the main throttle valve which is in this case so designed as to be readily adjustable to the small amounts of steam required, for example it may be in the form of a piston valve. However, for certain purposes it may be advantageous to maintain the compensating vessel at a low pressure sufficient for the auxiliary devices when the engine is stationary or idling by means of a reduction valve which is preferably of the automatically operating type.

In order that my invention may be clearly understood and readily carried into effect the same will now be more fully described with reference to the accompanying diagrammatic drawings which show one embodiment of a fireless locomotive constructed in accordance with the invention and having three accumulator tanks.

Fig. 1 is a diagrammatic drawing showing an embodiment of my invention;

Fig. 2 is a cross-sectional view of a locomotive embodying my invention;

Fig. 3 is a cross-sectional view on an enlarged scale of a valve shown in Fig. 2; and

Fig. 4 is an enlarged view of a pressure responsive device shown in Fig. 2.

Referring to the drawings, reference character 1 designates the lower accumulator tanks which are arranged horizontally (only one of the two tanks which are placed side by side is shown in the drawings) and entirely filled with water. 2 designates the upper tank which constitutes the evaporating vessel and the steam chamber. The steam is drawn off through the pipe 3, in which

a shut-off member 4 and a throttle member 5 are disposed. The throttle member 5 is, in the embodiment illustrated, adapted at the same time to serve as the locomotive regulator. The valve is provided with an arm 45 connected by means of a link 46 with one end of a pivoted arm 47. A link 48 connects the other end of arm 47 with a collar 49 having threaded engagement with a vertical shaft 50. A hand wheel 51 is secured to the shaft and rotation of the wheel causes the collar 49 to move up or down, thus pivoting valve arm 45 in one direction or the other. Downward movement of the collar, which causes pivoting of the valve arm in a counter-clockwise direction, closes the valve.

The steam, is throttled by the throttle member 5 to the normal working pressure of the locomotive and is superheated in the superheating devices 6 and then is conveyed to the compensating vessel 7. The heating portion of the superheater may either be designed as a tubular coil, preferably located in the upper reservoir, or it may comprise elements connected in parallel in all three tanks, being in the latter case designed for example for simplicity's sake as a twin pipe, as illustrated in the drawings.

The compensating vessel 7 is preferably arranged so as to be inclined slightly toward the place *a* at which the steam for the auxiliary devices is withdrawn. Thus, any condensation in vessel 7 will be discharged through the auxiliary devices and not through the engine cylinder.

A pipe 8 connects the vessel 7 with the locomotive cylinder 10 and a shut-off valve 9 is arranged in said pipe. This valve, which is shown more in detail in Fig. 3, includes a rotatable plug 30 provided with valve ports 31, 32 and 33 positioned within a housing having ports 34 and 35. As shown in Fig. 3, none of the ports are in registry and hence flow through the valve is prevented. However, a slight rotation of the plug 30 in either direction brings two of the ports in the plug into alignment with the housing ports to permit flow.

An arm 36 is secured to valve plug 30 and has a pin and slot connection with the shift rod 37 of the valve gear, here shown as being of the conventional Walschaert type. As is well known, this valve gear has forward, neutral and reverse positions and the connection thereto of the valve 9 is such that the latter is closed when the valve gear is in neutral position and is open when the gear is in either forward or reverse position. The shift rod 37 is connected through a bell crank lever 38 and a link 39 with a collar 40 having threaded engagement with a vertical shaft 41. A horizontal shaft having crank handles 43 rotates shaft 41 through bevel gears 44 to thus raise or lower collar 40. The other end of the shift rod 37 is pivotally connected to the arm 70. The arm 70 is fixed to the stud 72, an end view of which is shown in the drawings as pivoted in the bracket 73. The arm 71 is also fixed to the stud 72 so that it rotates with the stud 72 and the arm 70. The arm 74 pivotally connects the arm 71 and the arm 75, and the rear end of the arm 75 is pivotally connected to the swinging rod 76. The forward end of the rod 77 is also pivotally connected to the swinging rod 76 and the rear end of the rod 77 is pivotally connected to the rocker arm 78. The arm 78 is fixed to the rotating valve-operating-arm 79, an end view of which is shown in the drawings. The arm 79 is fixed to the valve mechanism in the cylinder 10 and transmits reciprocating motion to

this valve. The concurrent rotation of the arms 78 and 79 is also limited by the adjusted position of the arm 71. The valve operating arms 36 and 78 are thus interconnected and may be currently adjusted by the shift rod 37.

While the linkage 39, 38, 37, 70 and 71 of the Walschaert gear remains in one of its fixed adjusted positions the swingably pivoted linkage 74, 75, 76, 77, 78 and 79 is still free to reciprocate when actuated by well known connection to the driving wheels, as one end of the rod 75 is slidably connected at 80 to the pivoted rod 81.

In order to safeguard the compensating vessel 7 and the locomotive cylinder 10, in the case of locomotives of larger capacity, safety valves 11 are arranged in the line 3 in front of the superheater and in the line 8 in front of the cylinder 10, said safety valves being so proportioned that the two of them can allow the maximum amount of steam passed by the regulator 5 to escape.

In order to prevent the safety valves from blowing off every time the regulator 5 is opened wide, which would result in loss of steam, said regulator is advantageously partly or entirely closed, by means of a steam piston 55 adapted to act upon the arm 47, when the pressure in the compensating vessel 7 reaches maximum permissible value. Piston 55 is reciprocably mounted in a cylinder 56 which is connected to equalizer vessel 7 by means of a conduit 51. A spring 58 tends to move the piston to the right, as viewed in Fig. 4, against the force exerted by the steam. The piston 55 is secured to a piston rod 59 which is connected by means of a link 60 with an arm 61. This arm is rigidly connected to arm 47. Consequently, upon a sufficient increase in pressure in vessel 7 to overcome the force of spring 58, the piston is moved to the left, thus pivoting arms 61 and 47 in clockwise direction. This in turn pivots valve arm 45 in a counter-clockwise direction to close the valve 5 more or less, thus reducing the supply of steam to vessel 7. In this manner the regulator 5 cannot be opened further when the maximum permissible pressure is reached in the compensating vessel 7, while when such pressure is exceeded said regulator is closed sufficiently to prevent a further increase in pressure.

A further advantage of the arrangement illustrated in the drawings is afforded by the charging valves 18 and 19 and by the connecting line 20 between the reservoirs being disposed at that end of the locomotive opposite the driver's cab, so that the said cab is in no way encumbered by high pressure lines.

As the train heating and other auxiliary devices, such as the whistle and the like, associated with the locomotive, require only low pressure steam, the exhaust steam from the cylinder is according to the invention used for operating said devices. The drawings illustrate such an arrangement and on reference thereto it will be seen that a discharge pipe 13 is connected to the exhaust line 12, a reaction check valve 14 being located in the pipe 13. In order to increase the pressure of the exhaust steam a steam jet compressor 15 is provided which, in the constructional form illustrated in the drawings is supplied with condensation steam from *b* behind the shut-off member 9 which latter is, as above mentioned, coupled to the control. By this arrangement automatic dependency of exhaust steam and additional steam is obtained.

A check-valve 16 is arranged behind the steam jet compressor 15, and preferably also a com-

pensating vessel 17, the additional steam for the compressor being if necessary automatically regulated in accordance with the condensation steam pressure.

What I claim and desire to secure by Letters Patent of the United States is:

1. In a fireless locomotive, a high pressure steam accumulator, a pressure equalizing vessel, conduit means for conveying steam from said accumulator to said vessel, a throttling device in said conduit, a working cylinder, a valve for controlling supply of steam to said cylinder, a valve gear for operating said valve, means for shifting said gear to forward, neutral and reverse positions, a conduit for supplying steam from said vessel to said valve, a shut-off valve in the last mentioned conduit, and means interconnecting said shut-off valve with the valve gear shifting means operative to close the shut-off valve when said gear is in neutral position and to open said shut-off valve when the gear is in forward or reverse positions.
2. In a fireless locomotive, a high pressure steam accumulator, a working cylinder, conduit means for conveying steam from said accumu-

25 lator to said cylinder, a throttling device disposed in said conduit, a pressure equalizing vessel disposed in said conduit between said throttling device and said cylinder, means for interrupting flow of steam in said conduit from said vessel to said cylinder, manually operable means for adjusting said throttling device to control the flow of steam therethrough for varying the power output of the locomotive, and pressure responsive means actuated by rise in pressure in said vessel to close said throttling device.

3. In a fireless locomotive, a high pressure steam accumulator, a pressure equalizing vessel, conduit means for conveying steam from said accumulator to said vessel, a working cylinder, a conduit for supplying steam from said vessel to said cylinder, valve means for controlling the flow of steam from said accumulator to said cylinder, a shut-off valve in the last mentioned conduit, and means interconnecting said shut-off valve with said valve means to close the shut-off valve when said valve means stops the flow of steam from said accumulator to said cylinder.

PAUL GILLI.
